COMPACT

Johanna Beseke, Minneapolis, Minn.

Application October 5, 1946, Serial No. 701,540

4 Claims. (Cl. 132—83)

1

This invention relates to a compact and particularly to a structure of compact including a mirror and an illuminating means. Girls and women now wish frequently to examine and refresh their makeup. It is often desirable to do this in the dark or where there is a very poor light. Ladies' restrooms and retiring rooms are often very poorly lighted. It is desirable therefore to have a compact with a mirror and means for illuminating the same and the face of the user.

It is an object of this invention therefore to provide a compact adapted to contain a battery and a lamp bulb illuminated thereby, together with a mirror, said lamp bulb being positioned in respect to said mirror to give convenient and efficient illumination.

It is a further object of the invention to provide a compact comprising a comparatively shallow casing, a battery, preferably of the dry type, disposed in one end of said casing, the same having a lamp socket at one end with a lamp bulb fitting therein and extending upwardly therefrom, together with a mirror disposed adjacent said lamp bulb, said bulb projecting above the surface of said mirror.

It is more specifically an object of the invention to provide a compact comprising a comparatively shallow casing preferably of substantially rectangular form in plan, a flashlight battery disposed in one end of said casing having a lamp socket at its inner end, a lamp bulb disposed in said socket and extending upwardly therefrom, a movable plate of approximately the same area as said casing, said plate being positioned with one end portion disposed over said battery, a mirror carried by said end portion having its reflecting surface directed upwardly, said surface being somewhat below said lamp bulb, said mirror being disposed between said bulb and one end of said casing, said plate at its other end portion being provided with chambers, one of which is adapted to receive rouge and a rouge puff or pad and the other of which is adapted to receive a lipstick, coin or other article-receiving chambers being formed beneath said plate. The cover of said casing can conveniently contain powder and a powder puff.

These and other objects and advantages of the invention will be fully set forth in the following description made in connection with the accompanying drawings in which like reference characters refer to similar parts throughout the several views and in which:

2

Fig. 1 is a perspective view of the compact with the lid raised;

Fig. 2 is a perspective view of the compact in closed position;

Fig. 3 is a plan view with the lid raised, as in Fig. 1; some parts being broken away;

Fig. 4 is a view in front elevation with the lid closed, some parts being broken away and others

Fig. 5 is a vertical section taken on line 5—5 of Fig. 4;

Fig. 6 is a vertical section taken on line 6-6 of Fig. 3.

Fig. 7 is a vertical section taken on line 7—7 of Fig. 3, said sections being taken as indicated by the arrows.

Referring to the drawing, a compact is shown comprising a casing 10. While this casing could be variously formed, in the embodiment of the invention illustrated it is shown as substantially rectangular in plan with somewhat rounded corners and substantially rectangular in transverse and longitudinal cross section. Casing 10 is provided with a lid or cover 11 preferably hinged to said casing at one end by hinges 12, said cover 11 preferably having a depending flange 11a adapted to fit around the top of casing 10. Flange 11a will preferably be bent outwardly slightly at one side, as shown at 11b, to form a finger-hold for raising cover 11 and a closing clasp or catch of some type (not shown) may be provided. A battery casing 13 is provided adapted to contain one or more dry battery cells 13a of the flashlight type. Casing 13 is disposed in casing 10 preferably with its bottom engaging one end of casing 10 and disposed substantially centrally of said casing transversely thereof, and between partitions 10c secured to the bottom of casing 10. A spring 16 of plate

40 form is secured to one partition 10c and engages casing 13 to hold it in place. Battery casing 13 will be provided with a lamp socket 13c adapted to receive a lamp bulb 14 which projects upwardly from socket 13c. Battery casing 13 will 45 be provided with a suitable switch 13b preferably of the common sliding type for opening and closing the circuit for lamp bulb 14. A plate 15 is provided which will be movable relatively to casing 10, and while said plate could be variously arranged, preferably it is adapted to fit in and

50 arranged, preferably it is adapted to fit in and be pressed into casing 10 and be frictionally held therein. Plate 15 carries at one end a mirror 18 having its reflecting surface directed upwardly, said mirror thus being at the top of plate
55 15. Mirror 18 is disposed at one end portion of

plate 15 and in the embodiment of the invention illustrated extends over substantially half of said plate. Plate 15 is provided with an opening through which lamp bulb 14 projects. Mirror 18 is thus disposed between lamp bulb 14 and one end of casing 10 and lamp bulb 14 is disposed well above the surface of mirror 18. Plate 15, which is substantially of the same area as the inside of casing 10, has a depression 15a formed therein forming a shallow chamber adapted to contain rouge and a rouge puff or applying pad 20. Depression 15a and the chamber therein are shown as circular in plan and rouge puff 20 substantially fits in said chamber thus holding the powder therein. A plate 17 covers depression 15a and is hinged to plate 15 and has a finger-hold 17a for lifting the same. Plate 15 is also provided adjacent one side with a depression 15b forming a trough-shaped chamber adapted to receive a lipstick 21. Preferably partitions 10a extend partially across casing 10 in substantial alignment with the inner end of battery casing 13. Chambers 10b are thus formed at either side of casing 13 and these will be covered by plate 15. Plate 15 will preferably have a portion 15c at one end bent upwardly somewhat to form a finger-hold for raising said plate. There will also be a chamber 10d beneath plate 15 at one side of partitions 10a and at one side of depression 15b. Chamber 10d may be used to hold coins or other articles as may also the chambers 10b. Cover 11 may have a portion 11c bent upwardly slightly if necessary to accommodate lamp bulb 14 and the outer side of said cover could be provided with some ornament 23 to obscure said portion 11c. Cover 11 will preferably have a lining sheet 25 of thin paper or fabric and powder 26 will be carried in said lid. A fine screen or porous fabric 27 overlies powder 26, the same having a rim 27a extending thereabout adapted to fit in cover 11. A powder puff 28 of usual form overlies the member 27 and is supplied with powder passing through member 27.

In operation the compact will be carried in closed condition as shown in Fig. 2. When the user desires to refresh her makeup, cover 11 will be raised, as shown in Fig. 1, and switch 13b will be moved to illuminate bulb 14. The compact can now be held in position with mirror 18 substantially vertical and the face of the user can be brought close to the mirror and said face and mirror will be effectively illuminated by bulb 14. This illumination is greatly increased in efficiency by having the bulb 14 disposed above the surface of mirror 18. The user can use the lipstick 21, the rouge puff 20 and powder puff 28, and when the makeup operation is completed, switch 13b will be moved to extinguish lamp bulb 14 and cover 11 can then be closed. Plate 15 can be easily raised by finger-hold 15c. Access is thus given to the chambers 10b, 10c and 10d, and access is also given to battery casing 13 should it be desired to renew the dry cells 13a.

From the above description it will be seen that I have provided a simple and efficient structure of compact comprising illuminating means for a mirror and one which can be very conveniently used for refreshing a makeup where there is little or no light. The compact can be carried just the same as any ordinary compact and the same will be finished in a pleasing manner. It will be apparent that the device will have a high degree of utility for the purpose intended.

It will of course be understood that various changes may be made in the form, details, ar-

angement and proportions of the parts, without departing from the scope of applicant's invention, which generally stated, consists in a structure of compact capable of carrying out the objects above set forth, in the parts and combinations of parts disclosed and defined in the appended claims.

What is claimed is:

1. A compact comprising a casing of comparatively shallow depth, a battery disposed in one end of said casing having a lamp socket at its inner end, a lamp bulb fitting in said socket and extending upwardly therefrom, a plate movable relatively to said casing and constructed and arranged to be positioned over said battery and substantially parallel to the bottom of said casing, said plate having an opening therethrough through which said lamp bulb projects when said plate is so positioned, a mirror carried by said plate having its reflecting surface at the upper side thereof, said bulb extending upwardly to a point above the surface of said mirror and being disposed substantially centrally transversely of said mirror, and a cover for said casing.

2. A compact comprising a casing having a chamber therein of shallow depth, a battery in one end of said chamber having a lamp socket at its inner end, a lamp bulb fitting in said socket and extending upwardly therefrom, a plate of substantially the same area as said casing movable relatively to said casing and adapted to be disposed in horizontal position over said battery, said plate having a hole therethrough through which said lamp bulb projects, a mirror carried by the end portion of said plate extending over said battery, the same having its reflecting surface at its upper side and being disposed between said bulb and one end of said casing, said lamp bulb extending upwardly above the said surface of said mirror, said plate having a slot therein at one side of said mirror, a switch for said lamp movable in said slot and a cover for said casing adapted to contain powder.

3. A compact comprising a casing having a chamber therein of shallow depth, a battery in one end of said chamber having a lamp socket at one end, a lamp bulb fitting in said socket and extending upwardly therefrom, a plate of substantially the same area as said casing movable relatively to said casing and adapted to be disposed in horizontal position over said battery, said plate having a hole therethrough through which said lamp bulb projects, a mirror carried by the end portion of said plate extending over said battery, the same having its reflecting surface at its upper side and below said lamp bulb, said plate at its other end portion having a depression therein at one side forming a chamber for rouge and a rouge puff and having a chamber adjacent said last mentioned chamber adapted to receive a lipstick and a cover plate for said depression.

4. A compact comprising a casing of shallow depth, a battery disposed at one end of said casing having its top surface below the top of said casing and having a lamp bulb at one end, said bulb projecting upwardly, a partition extending across said casing at the inner end of said battery, partitions at the sides of said battery whereby chambers are formed at either side of said battery, a plate movable relatively to said casing and adapted to be positioned over said battery substantially parallel to the bottom of said casing, said plate having an opening therethrough through which said lamp bulb extends, a mirror carried by said plate having its reflecting surface disposed

upwardly, said mirror being disposed over said battery, said plate having a slot therein adjacent said mirror, a switch for said lamp movable in said slot, said plate having chambers formed therein at its other end portion adapted to receive respectively rouge and a rouge puff and a lipstick respectively, a chamber being formed beneath said last mentioned end portion of said plate and the bottom of said casing and a cover for said casing.
